UNITED STATES PATENT OFFICE.

CHARLES E. HARTHAN, OF LYNN, MASSACHUSETTS, ASSIGNOR TO THE GENERAL ELECTRIC COMPANY, OF NEW YORK.

DESIGN FOR AN ELECTRIC-ARC-LAMP CASING.

SPECIFICATION forming part of Design No. 30,686, dated May 2, 1899.

Application filed February 7, 1898. Serial No. 669,452. Term of patent 14 years.

To all whom it may concern:

Be it known that I, CHARLES E. HARTHAN, a citizen of the United States, residing at Lynn, in the county of Essex, State of Massachusetts, have invented and produced a new and original Design for an Electric-Arc-Lamp Casing, (Case No. 733,) of which the following is a specification.

The accompanying drawing shows an electric-arc-lamp casing illustrating the invention.

The leading feature of the design is the configuration of the casing, which casing, as appears from the drawing, consists of a cylindrical body having enlarged cornices or moldings at the upper and lower ends.

A indicates the main body of the casing which is intended to inclose the lamp mechanism and is made in the form of a cylinder.

Mounted respectively at the top and the bottom of the cylinder are cornices or moldings G and H. These cornices are similar in construction, except that they are reversed with respect to each other. Situated under the lower cornice H is a ring D, that is intended to rest upon the lamp-globe. Each cornice is provided with a central bead F, and from this point are a series of rings gradually decreasing in diameter as they recede therefrom.

What I claim is—

The design for an electric-arc-lamp casing, as herein shown and described.

In witness whereof I have hereunto set my hand this 2d day of February, 1898.

CHARLES E. HARTHAN.
